UNITED STATES PATENT OFFICE.

HARRY A. VANCE, OF EMPIRE, OHIO, ASSIGNOR OF ONE-THIRD TO L. F. BROWN, OF EMPIRE, OHIO.

SELF-LEVELING TABLE.

No. 807,099.

Specification of Letters Patent.

Patented Dec. 12, 1905.

Application filed October 27, 1904. Serial No. 230,258.

To all whom it may concern:

Be it known that I, HARRY A. VANCE, a citizen of the United States of America, residing at Empire, in the county of Jefferson and State of Ohio, have invented certain new and useful Improvements in Self-Leveling Tables, of which the following is a specification, reference being had therein to the accompanying drawings.

This invention relates to certain new and useful improvements in tables, and has for its object to provide a self - leveling table which will be comparatively simple in construction, strong and durable, and highly efficient when used.

The table as contemplated by me is particularly adapted for use upon vessels and trains where a rolling motion is experienced, and I have constructed my improved table whereby the same may be easily and quickly applied to the floor of a compartment in which it is to be used.

With the above objects in view reference will be had to the drawings accompanying this application, wherein like numerals of reference designate corresponding parts throughout both views, in which—

Figure 1 is a side elevation of my improved table, showing the floor of a room in section and having my improved table mounted therein; and Fig. 2 is a transverse sectional view taken on the line *x* *x* of Fig. 1.

To put my invention into practice, I provide the floor of the compartment in which the table is to be mounted with an opening 1, and in said opening I secure by bolts and nuts 2 2 a plate 3, which is formed with a central enlargement 4, and the faces of the enlargement are provided with the concavities 5 5, these concavities being formed of such a depth as to provide an opening 6 between the concavities, and in this opening and the concavities 5 5 is mounted a table.

The table as constructed by me consists of a top 7, to the under face of which is secured a plurality of legs 8 8, which are curved and meet in a common center, as indicated at 9. The center of these legs is provided with a semispherical portion 10, that seats in the upper concavity 5. Centrally of the semispherical portion 10 is formed a screw-threaded aperture in which is secured the screw-threaded end of a rod 11, and the lower

end of this rod is screw-threaded to receive a nut 12, and upon the lower end of said rod is mounted a plurality of weights 14.

From the foregoing description, taken in connection with the drawings, it will be observed that the table is pivotally mounted within the plate 3 and that the same will be held in a vertical position within this plate by the weight 14, suspended from the table. Should the floor of the compartment in which the table is mounted be inclined, the rod 11 will maintain a vertical position, this being facilitated by the moving of the semispherical portion 10, within the upper concavity 5, and the lower concavity will permit of the inclination of the floor without interfering with the rod 11. The table-top 7 will at all times be held in a level position, and the rocking or rolling movement of the compartment in which it is mounted will not displace any articles that may be placed upon the table.

While I have herein shown the preferred manner of constructing my improved table, it is obvious that various changes may be made in the details of construction without departing from the general spirit and scope of the invention.

Having fully described my invention, what I claim, and desire to secure by Letters Patent, is—

1. The combination with a floor having an opening therein, and a plate arranged in said opening and having a lateral flange, said flange being affixed to the floor and having a concavity in its top, of a table-top, a plurality of legs secured to said table-top, a semispherical portion carried by said legs and seating in the concavity in said plate, a rod attached to said semispherical portion and extending through the plate and a weight carried by said rod below the floor.

2. The combination with the floor of a compartment said floor having an opening formed therein, of a plate secured in said opening, said plate having concavities formed therein, a table, a semispherical portion carried by the table and mounted in one of said concavities, removable weights mounted below the floor of the compartment and connecting with said table for maintaining the level thereof, substantially as described.

3. The combination with a floor having an opening therethrough, of a plate arranged

over said opening and attached to the floor, said plate being formed with a concavity in its upper side, a table-top, a plurality of legs secured to said table-top and meeting below the center of the same, a semispherical portion carried by said legs at their meeting-point, said semispherical portion seating in the concavity of said plate, a rod screwing into said semispherical portion and a plu-

rality of removable weights carried on said rod below the said floor.

In testimony whereof I affix my signature in the presence of two witnesses.

HARRY A. VANCE.
